UNITED STATES PATENT OFFICE.

THOMAS O. PAYNE, OF VICKSBURG, MISSISSIPPI.

FIRE-BLOWER.

SPECIFICATION forming part of Letters Patent No. 519,733, dated May 15, 1894.

Application filed January 17, 1893. Serial No. 458,720½. (No model.)

To all whom it may concern:

Be it known that I, THOMAS O. PAYNE, a citizen of the United States, residing at Vicksburg, in the county of Warren and State of Mississippi, have invented certain new and useful Improvements in Fire-Blowers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in fire blowers, and it has for its object the provision of a blower that can be made to fit different size fire places, and that can be adjusted to different heights therein. To attain these objects I provide the body of the blower with a removable rim that is secured to the body so as to be flexible, and the body of the blower is provided with an adjustable bracket by means of which the blower can be made to stand at different heights upon the grate before which it is placed. The invention further consists in the novel construction and arrangement of the parts hereinafter described, illustrated in the drawings, and more 25 particularly pointed out in the claims hereunto appended.

In the drawings, Figure 1 is a front elevation of the blower in position. Fig. 2 shows a vertical section thereof, and Fig. 3 is a view 30 showing the flexible rim.

Similar letters indicate corresponding parts in all the figures.

F is the body of the blower and is provided with a handle as is usual. In the lower cen-

tral portion of the blower is a slot J, into 40 which is set a set screw K, which passes through and is secured to the inside of the blower to a lug or bracket L, as shown. The lug and screw are adjusted vertically in the slot J, as is evident. Around the body F of 45 the blower is an adjustable rim E secured to the body of the blower so as to be flexible. This rim is secured to the body of the blower by separable hinges m, m, m, or in any other suitable manner that will allow the detach- 50 ing of the rim E from the body F of the blower, or its free adjustment to the fire place. On the upper portion of said blower and also of said rim, on the inside thereof, is a catch or bracket i, i, for helping to hold the said 55 blower to the fire place. When a small blower is needed or is necessary the rim E can be removed, by slipping the hinges h, h, h, as is evident.

Having thus described my blower, I claim— 60

1. In a fire blower of the character described the combination of a body F, provided with means for adjusting the blower vertically, with a removable rim secured to the body, as set forth. 65

2. In a fire blower of the character described the combination of a body F, a slot J and a thumb screw and bracket adjustably secured in said slot for adjusting the blower vertically, and a removable rim secured to 70 the said blower by hinges or otherwise, as set forth.

In testimony whereof I affix my signature in presence of two witnesses.

THOMAS O. PAYNE.
